UNITED STATES PATENT OFFICE.

THADDEUS D. McCALL, OF IMPERIAL, CALIFORNIA.

OIL BARREL.

Application filed June 24, 1926. Serial No. 118,198.

This invention relates to improvements in oil barrels, and the general object of the invention is to provide an oil barrel with means whereby the barrel, after the oil has been removed therefrom, may be readily converted into a stove.

A more particular object is to provide a barrel of the character stated which will be simple in construction, efficient in use and inexpensive to manufacture.

With the above and other objects in view, the invention consists in the novel and useful provision, formation, construction, combination, association and relative arrangement of parts, members and features, all as herein-after described, shown in the drawing, and finally pointed out in claims.

In the drawing:

Figure 1 is a front elevation of an oil barrel embodying my invention, shown converted into a stove;

Figure 2 is a plan view of said barrel, as shown in Fig. 1;

Figure 3 is a vertical longitudinal section of the barrel shown closed for containing oil;

Figure 4 is a front view of the stove draft regulator applied to the faucet outlet in the lower front part of the barrel;

Figure 5 is a vertical section of the draft regulator taken on line 5—5 of Fig. 4;

Figure 6 is a vertical sectional view taken on the line 6—6 of Fig. 2, showing the stove lid fitted in the barrel inlet;

Figure 7 is a vertical sectional view taken on the line 7—7 of Fig. 2, showing the stove pipe fitted over the faucet outlet in the top of the barrel; and,

Figure 8 is a plan view of said barrel as shown in Fig. 3.

Corresponding parts in all the figures are designated by the same reference characters.

Referring with particularity to the drawing, I have shown a metal oil barrel A including a cylindrical wall a , a bottom a' , top a'' , faucet outlet 1 in the lower part of said cylindrical wall, and the cover 2 for said outlet, faucet outlet 3 in the top a' , and the cover 4 for said outlet, and the oil inlet 5 in the top, and the cover 6 for said inlet, the lower and upper edges of the cylindrical wall a extending respectively below and above the bottom a' and the top a'' . The cover 2 is bolted over the outlet 1 by bolts 7 and nuts 8, and is provided with a threaded opening 9 to receive the threaded end of a faucet (not shown) which opening is closed by a screw plug 10

when the faucet is not screwed thereon (see Fig. 3).

The outlet 3 in the top a'' of the barrel is formed with an upstanding external flange 11 over which is fitted the cover 4 which is formed with an external flange 12 bolted to the top by bolts 13 and nuts 14. The cover 4 is formed with a central depression 15 fitting in the outlet 3 and provided with a threaded faucet opening 16, which opening is closed by a threaded plug 17 when the faucet is not screwed in the opening, the depression 15 being adapted to position the top of the plug below the upper edge a'' of the cylindrical wall of the barrel.

The oil inlet 5 is formed with a countersunk internal annular flange 18 and the cover 6 is bolted to the barrel top a'' over said inlet by bolts 19 and nuts 20.

When the oil is removed from the barrel through faucets screwed in the openings 9 and 16, the nuts 8, 14 and 20 are unscrewed from the bolts 7, 13 and 19 respectively and the covers 2 and 4 removed from the outlets 1 and 3, and the cover 6 removed from the inlet 5. A draft regulator 25 is placed over the opening 1, which regulator comprises a plate 26, a concave-convex closure member 27, and a screw 28 seated in the center of said plate and swivelly connected in the center of said closure member by a swivel joint 29, there being a handle 30 on the outer end of said screw for turning the same. The plate 26 is provided with bolt holes 31 to receive the bolts 7, the nuts 8 being screwed on the outer ends of said bolts against said plate, whereby the regulator is secured on the barrel over the outlet 1. The plate 26 is provided with air draft inlets 32. When the screw 28 is screwed outwardly and the closure 27 moved outwardly from the plate 26, air passes between the closure and said plate through the inlets 32 into the barrel, the amount of air being regulated by the distance between the closure member and said plate as regulated by the screw 28. The cover 6 being removed from the inlet 5, fuel is introduced into the barrel through said inlet and a stove lid 35 is placed over said inlet upon the flange 18. The cover 4 being removed from the opening 3, a stove pipe 36 is fitted over the upstanding flange 11 around the outlet 3, through which outlet and pipe the products of combustion of the burning fuel pass.

It is obvious that many changes and variations may be made in the general and partic-

ular construction of the device and its parts and features, in relation to the recitals hereinabove made in that regard, in practicing the invention, and in adapting it to varying 5 conditions of use and service, without departing from the true spirit of the invention.

Having thus disclosed my invention, I claim and desire to secure by Letters Patent:

1. An oil barrel comprising a shell, heads 10 secured fluid-tight in the lower and upper ends respectively of said shell, said upper head being provided with an oil inlet and a faucet outlet, a cover for said inlet, means for detachably securing said cover fluid-tight 15 on said upper head over said inlet, a cover for said faucet outlet, means for detachably securing said cover fluid-tight on said upper head over said faucet outlet, said shell being provided with a faucet outlet in the lower 20 end thereof, a cover for said latter faucet outlet, and means for detachably securing said cover fluid-tight on said shell over said latter faucet outlet.
2. An oil barrel comprising a shell, heads 25 secured fluid-tight in the lower and upper ends of said shell respectively, said upper head being provided with an oil inlet and a faucet outlet, a depressed internal annular

flange formed around the edge of said oil inlet, a cover for said oil inlet, means for detachably securing said cover on said upper head over said oil inlet, an external annular upstanding flange formed around the edge of said faucet outlet, a cover for said faucet outlet, means for detachably securing said cover fluid-tight on said upper head over said faucet outlet, said shell being provided with a faucet outlet in the lower end thereof, a cover for said latter faucet outlet, and means for detachably securing said cover fluid-tight on said shell over said latter faucet outlet.

3. An oil barrel comprising a shell, heads secured fluid-tight in the lower and upper ends respectively of said shell, said upper head being provided with an oil inlet and a faucet outlet arranged diametrically opposite each other, said shell being provided with a faucet outlet arranged diametrically opposite the faucet outlet in said upper head, covers for said oil inlet and said faucet outlets respectively, and means for detachably securing said covers fluid-tight over said oil inlet and said faucet outlets respectively.

In testimony whereof, I have signed my name to this specification.

THADDEUS D. McCALL.
